[] Term: 14 Years

[21] Appl. No.: 35,894Primary Examiner*—Holly H. Baynham
Attorney, Agent, or Firm—Gerard F. Dunne[22] Filed: Mar. 8, 1995[57] CLAIM*Related U.S. Application Data

The ornamental design for a holder for baby wipes container, as shown and described.

[62] Division of Ser. No. 89,836, Jul. 12, 1993.

DESCRIPTION[52] U.S. Cl. D8/354

FIG. 1 is a perspective view of an embodiment of my invention;

[58] Field of Search D8/349, 354, 366,

FIG. 2 is a left side view of the embodiment of my invention with the opposite side being a mirror image;

D8/371, 373, 395; 248/231.8, 215, 229;

FIG. 3 is a top view of this embodiment of my invention;

52/96, 60, 222, 410; D6/320, 323, 325

FIG. 4 is a bottom view of this embodiment of my invention;

[56] References Cited

FIG. 5 is a front view of this embodiment of my invention; and,

U.S. PATENT DOCUMENTS

FIG. 6 is a back view of this embodiment of my invention.
